UNITED STATES PATENT OFFICE

167,213

DISPENSING CONTAINER FOR FLUFFED CREAM

Aaron S. Lapin, St. Louis, Mo., assignor to Reddi-Wip, Inc., St. Louis, Mo., a corporation of Missouri

Application October 19, 1948, Serial No. 149,178

Term of patent 14 years

(Cl. D58—17)

To all whom it may concern:

Be it known that I, Aaron S. Lapin, a citizen of the United States, residing in the city of St. Louis and State of Missouri, have invented a new, original, and ornamental Design for a Dispensing Container for Fluffed Cream, of which the following is a specification, reference being made to the accompanying drawing, forming part thereof.

In the accompanying drawing:

I claim:

The ornamental design for a dispensing container for fluffed cream, as shown.

AARON S. LAPIN.
